UNITED STATES PATENT OFFICE.

WILLIAM TREESE, OF SILVERTON, OREGON.

BLASTING-POWDER.

1,265,975.

No Drawing.

Specification of Letters Patent. Patented May 14, 1918.

Application filed April 16, 1917. Serial No. 182,495.

To all whom it may concern:

Be it known that I, WILLIAM TREESE, a citizen of the United States, residing at Silverton, in the county of Marion and State of Oregon, have invented certain new and useful Improvements in Blasting-Powder; and I do declare the following to be a full, clear, and exact description of the invention, such as will enable others skilled in the art 10 to which it appertains to make and use the same.

This invention relates to explosives and more particularly to blasting compounds.

The object of the invention is to provide 15 a composition of this character which may be quickly manufactured without resorting to the use of expensive machinery and dangerous manipulation and which when made will not explode by friction, will not explode 20 in open air, and may be extinguished should it become accidentally ignited.

In the explosive composition comprising 25 this invention, the following ingredients in or about the proportions stated, are employed:

Yellow wax	13%
Soap stock (saponifiable fatty material)	7%
Sulfur	21%
Niter	11%
Potassium chlorate	22%
Nitro-starch	26%

I do not confine myself to the exact proportions of the ingredients above stated as such proportions may be varied according to the strength of the explosive required and the use of said explosive is not confined to blasting purposes.

In manufacturing the powder the yellow wax and soap stock are placed in a kettle and heated to about 140° F. more or less;

The sulfur is then added to this mixture and the resulting product run through a screen. The niter ground fine and heated to about 100° F. or any suitable drying heat is also 45 added to the above specified ingredients by passing it through a fine sieve or screen and when well dried the potassium chlorate and nitro-starch are added. If desired, one or the other of the last mentioned ingredients 50 may be omitted and 48% of the other used, that is, 48% of potassium chlorate may be used or 48% of nitro-starch or 22% of potassium chlorate and 26% of nitro-starch, these two ingredients being substantial equivalents and the one which is the cheapest is 55 preferably used.

The yellow wax and soap stock serve to prevent friction between the active ingredients so that jarring of the powder will not 60 cause it to ignite or explode and should it accidentally ignite, it may be extinguished in the ordinary manner. In order to cause this powder to explode it is necessary that it be confined and ignited.

Owing to the fact that this powder is not explosive until confined and ignited, no 65 precaution need be taken in handling it.

I claim:

A composition of matter for use as a blasting explosive, comprising approximately 70 13% yellow wax, 7% soap stock, 21% sulfur, 11% niter, 22% potassium chlorate and 26% nitro-starch.

In testimony whereof I have hereunto set 75 my hand in the presence of two subscribing witnesses.

WILLIAM TREESE.

Witnesses:
